UNITED STATES PATENT OFFICE.

ROBERT F. MATHEWS, OF NEWARK, NEW JERSEY, ASSIGNOR TO THE HEATHER-MATHEWS CO., A COPARTNERSHIP CONSISTING OF RICHARD C. HEATHER AND ROBERT F. MATHEWS, OF NEW YORK, N. Y.

DESIGN FOR A COMBINATION LAMP AND GLOBE.

Application filed July 11, 1927. Serial No. 22,724. Term of patent 14 years.

To all whom it may concern:

Be it known that I, ROBERT F. MATHEWS, a citizen of the United States, residing in Newark, in the county of Essex and State of New Jersey, have invented a certain new, original, and ornamental Design for Combination Lamps and Globes, of which the following is a specification, reference being

had to the accompanying drawing, which is a side elevation of a combination lamp and globe showing my new design.

I claim:

The ornamental design for a combination lamp and globe as shown.

ROBT. F. MATHEWS.
